CONTROLLER FOR MOBILE GLOW
DISCHARGE SYSTEMS

Hal C. Mettler, Alhambra, Calif., assignor of one-half to Lloyd Spencer, South Pasadena, Calif.

Application May 8, 1944, Serial No. 534,624

6 Claims. (Cl. 177—346)

1

My invention relates to controllers for mobile glow discharge systems; that is, to devices for producing mobile or progressive illumination in so-called "neon" tubing so as to give the effect of writing. The present invention is a continuation in part of my copending application filed November 12, 1940, Serial Number 365,206, entitled Low frequency mobile glow discharge system, which issued August 1, 1944 as Patent Number 2,354,696.

Among the objects of my invention are:

First, to provide a controller for mobile glow discharge systems wherein an auto-transformer of the carbon-brush type is employed to control the input voltage to limited current or "neon" transformers connected with a glow discharge tube system of the type more fully disclosed in the above mentioned patent application.

Second, to provide a controller for mobile glow discharge systems which is inherently capable of controlling a large amount of electrical energy so that signs of substantial size may be operated.

Third, to provide a controller of this character which is capable of causing mobile glow discharge in a plurality of glow discharge tubes either simultaneously or in sequence.

Fourth, to provide a controller of this character wherein several brush elements are caused to move in sequence from the "zero" end to the one-hundred percent end of an auto-transformer and thereafter remain in electrical association with said one-hundred percent end until all brush elements are in contact therewith, whereby illumination may be caused to progress from one glow discharge system to a succeeding glow discharge system without observable break or hesitation or interruption in the "writing" effect thus produced.

Fifth, to provide a controller of this character wherein an auto-transformer is provided with dual windings arranged so that brush elements may move continuously from a zero end to a one-hundred percent end and return, several brush elements being employed and displaced in out-of-phase relation to produce a novel mobile effect in associated mobile glow discharge tubing systems.

With the above and other objects in view, reference is directed to the accompanying drawings, in which:

Figure 1 is a diagrammatical view of a glow discharge tubing system adapted for operation by my controller.

Figure 2 is a diagrammatical view of one form of my controller shown arranged to control several glow discharge tubing systems simultaneously.

2

Figure 3 is a diagrammatical view of a modified form of my controller wherein several glow discharge tubing systems are controlled in sequence.

Figure 4 is a diagrammatical view of another modified form of my controller wherein the illumination of several glow discharge tubing systems is caused to progress and recede in time displaced relation.

Figure 5 is a transverse sectional view of a neon tube employed in conjunction with my controller.

10 The controller herein employed is particularly designed for use in conjunction with the mobile glow discharge system described in the aforementioned patent application. Briefly, said system comprises one or more glow discharge tubes 1, commonly designated "neon" tubes although they may contain any one of the several rare gases or mercury vapor. The glow discharge tubes have end electrodes 2 and 3, and intermediate electrodes 4. The intermediate electrodes are connected through resistors 5 to ground, the end electrode 3 is connected directly to ground, while the end electrode 2 is connected to one side of the secondary 6 a limited current or "neon" 15 transformer 7. The outer end of said secondary is grounded. The tubing is provided with a metal coating 8 along its back side which coating is grounded.

20 The primary 9 of the neon transformer is connected to a source of power supply through a controller indicated generally by 10 in Figure 1. The controller and its association with the glow discharge tubing system is the subject of this application and consists essentially in a novelly arranged transformer with moving brushes and a drive means therefor.

25 With reference to Figure 2, a controller transformer 21 is shown. The controller transformer is essentially an auto-transformer in which the core is ring-shaped with a single torus winding 22 connected at its ends to a source of low frequency current. A brush 23 and its supporting arm is mounted on a shaft 24 driven by a motor 25. The brush is arranged to wipe around the winding 22. The shaft carries a slip ring 26 connected with the brush 23. A contact 27 rides on the slip ring. It should be noted that the contact 27 may revolve with the brush 23, in which case the slip ring 26 is stationary. In addition to the slip ring, the shaft 24 drives a cam 28 which controls a switch 29 in series with the contact 27.

30 A lead 30 extends from the switch 29 to one end of the primary of the limited current trans-

55

former 7 while the other end thereof is connected to a leg of the input line.

The connections are such that the potential across the primary 9 varies from zero to full line voltage as the brush 23 moves around the winding 22. The full or 100% end of the winding 22 is provided with a short contact strip 31 terminating adjacent the "zero" end of the winding. The cam 28 is so arranged that the switch 29 is opened as the brush 23 moves from the contact strip 31 to the "zero" end of the winding, thus avoiding shorting the auto-transformer.

The controller 10 may control several glow discharge systems of the type shown in Figure 1 by controlling several neon transformers as shown in Figure 2, in this case four glow discharge systems are shown. As a consequence, illumination may be caused to progress in all systems simultaneously.

In the construction shown in Figure 2, the transformer winding 22 occupies virtually the entire circumference of the transformer core; in Figure 3, however, is illustrated a modified arrangement wherein the extent of the winding is reduced. Thus, the controller transformer 41 shown in Figure 3 is provided with a winding 42 connected with an elongated contact segment 43 at its 100% end. Several brushes 44 are provided. These are arcuately displaced and connected to individual slip rings 45. Independent circuits are provided through contacts 45^a and leads 46 to transformers 7. A switch 47 is provided between the 100% or segment end of the winding 42 and the supply lead thereto. This switch is controlled by a cam 48.

All, or at least all but one, of the slip rings 45 include insulated segments 49 which differ in length in proportion to the circumferential displacement of the brushes 44 so that the ends of all slip rings provided with insulated segments are opposite the contacts 45^a simultaneously with operation of the cam 48 to open the switch 47. The leading brush is at such time at the extremity of the contact segment 43 and about to move onto the "zero" end of the winding. The auto-transformer 41 is opened by the switch 47 to permit movement of the leading brush onto the "zero" end of the winding, and the other brushes onto their respective insulated segments 49.

The circuit controlled by each brush 44 may include one or several limited current or neon transformers as in the case of the construction shown in Figure 2. The circumferential displacement of the several brushes are such that as one glow discharge tubing system becomes fully illuminated, glow discharge begins in the next system without break or pause. The brushes 44 may have limited arcuate adjustment relative to each other so that the timing from circuit to circuit may be adjusted to produce smooth continuity.

Reference is now directed to Figure 4. In the construction here shown, the controller transformer 51 is provided with two windings 52 and 53 each occupying one half the circumference. The windings are reversed so that their "zero" ends and their 100% ends are adjacent. Several, in the case illustrated three, brushes 54 are mounted in equally spaced relation about a common shaft. The brushes are connected by slip rings and contact members, not shown, to three circuits each comprising one or more neon transformers and corresponding glow discharge systems. Because of the spacing of the brushes 54, the illumination is caused to progress in the glow

discharge systems at different times; that is, as one system is at full brilliancy, another is "writing" and the third is "unwriting." This arrangement is particularly effective to illuminate indirectly the letters of a sign by using a different color of light in each system. The colors blend from one to the other to produce a beautiful rainbow effect.

Although I have shown certain embodiments of my invention, I do not wish to be limited thereto, but desire to include in the scope of my invention the constructions, combinations, and arrangements substantially as set forth in the appended claims.

I claim:

1. In a mobile glow discharge system: a plurality of glow discharge tubing units, each unit including continuous external metallic elements forming with the gaseous content of said tubing a distributed capacity, a series of electrodes spaced along the length of said unit, resistors connected to the intermediate electrodes; a high potential, limited current transformer for each unit, each transformer including a secondary connected to the extreme electrodes of its unit and a primary connected to a source of commercial low frequency current; one end of the secondary of each transformer, said metallic elements and an end electrode of the corresponding unit being electrically connected and establishing a common potential, said resistance elements bridging between their respective electrodes and said common potential; an auto-transformer including a winding and at least one moving brush electrically connected with the primaries of said limited current transformers to cause the voltage thereacross to vary between a predetermined minimum and a predetermined maximum.

2. In a mobile glow discharge system: a plurality of glow discharge tubing units, each unit including continuous external metallic elements forming with the gaseous content of said tubing a distributed capacity, a series of electrodes spaced along the length of said unit, resistors connected to the intermediate electrodes; a high potential, limited current transformer for each unit, each transformer including a secondary connected to the extreme electrodes of its unit and a primary connected to a source of commercial low frequency current; one end of the secondary of each transformer, said metallic elements and an end electrode of the corresponding unit being electrically connected and establishing a common potential, said resistance elements bridging between their respective electrodes and said common potential; an auto-transformer including a torus shaped core; an arcuate winding occupying a portion of said core, a contact segment continuing from one end of said winding around said core, brushes adapted to rotate about said winding and contact segment in sequence, said winding and brushes connected with the primaries of said limited current transformers to cause the voltage across said primaries to vary in sequence from predetermined minimums to predetermined maximums as said brushes move toward and onto said contact segment, whereby illumination is caused to progress along said tubing units in corresponding sequence.

3. In a mobile glow discharge system, wherein each of a plurality of glow discharge tubing units incorporates a distributed capacity and resistance network between its ends to cause progressive ionization in said tubing unit as the input voltage across said unit from a low frequency source is

varied, the combination of a controller for varying said input voltage, comprising: limited current transformers having secondaries connected across said tubing units; an auto-transformer including a winding and, at least one moving brush electrically connected with the primaries of said limited current transformers, and means for driving said moving brush to cause the voltage thereacross to vary between a predetermined minimum and a predetermined maximum, thereby to cause a corresponding progression of ionization in said tubing units.

4. In a mobile glow discharge system, wherein each of a plurality of glow discharge tubing units incorporates a distributed capacity and resistance network between its ends to cause progressive ionization in said tubing unit as the input voltage across said unit from a low frequency source is varied, the combination of a controller for varying said input voltage, comprising: limited current transformers having secondaries connected across said tubing units; and an auto-transformer including a torus shaped core; an arcuate winding occupying a portion of said core, a contact segment continuing from one end of said winding around said core, brushes adapted to rotate about said winding and contact segment in sequence, said winding and brushes connected with the primaries of said limited current transformers to cause the voltage across said primaries to vary in sequence from predetermined minimums to predetermined maximums as said brushes move toward and onto said contact segment, whereby illumination is caused to progress along said tubing units in corresponding sequence.

5. In a mobile glow discharge system, wherein each of a plurality of glow discharge tubing units incorporates a distributed capacity and resistance network between its ends to cause progressive ionization in said tubing unit as the input voltage across said unit from a low frequency source is varied, the combination of a controller for varying said input voltage, comprising: limited current transformers having secondaries connected across said tubing units; and a moving brush auto-transformer; a plurality of moving brushes thereon electrically connected to corre-

sponding limited current transformers for controlling the voltage thereof; means for driving said brushes in a predetermined sequence to effect corresponding sequence in the progression of illumination in said tubing units.

6. In a mobile glow discharge system, wherein each of a plurality of glow discharge tubing units incorporates a distributed capacity and resistance network between its ends to cause progressive ionization in said tubing unit as the input voltage across said unit from a low frequency source is varied, the combination of a controller for varying said input voltage, comprising: limited current transformers having secondaries connected across said tubing units; an auto-transformer including a torus shaped core and a pair of semi-circular windings each occupying approximately one-half the circumference of the core and wound in reverse relation to the other, said windings being joined at their extremities to form parallel coils; moving brushes adapted to rotate around said windings, said windings and brushes connected with corresponding limited current transformers to cause the voltage across their primaries to vary progressively from minimum to maximum and return, thereby to cause corresponding progression and regression of ionization in said tubing units, said brushes being displaced in their positions with respect to said windings whereby the cycles of progression and regression of ionization of said tubing units are correspondingly displaced.
